(57) **CLAIM**

The ornamental design for an LED bulb, as shown and described.

DESCRIPTION

FIG. 1 is a perspective view of front and top sides of an LED bulb according to a first embodiment showing our new design;

FIG. 2 is a front view thereof;

FIG. 3 is a rear view thereof;

FIG. 4 is a left side view thereof;

FIG. 5 is a right side view thereof;

FIG. 6 is a top view thereof and,

FIG. 7 is a bottom view thereof;

FIG. 8 is a perspective view of front and top sides of an LED bulb according to a second embodiment showing our new design;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The broken lines shown are included for the purpose of illustrating the unclaimed portions of an LED bulb and form no part of the claimed design. The different shading techniques used depict a contrast of appearance only and does not represent a particular color, material, or texture.
